(57) **CLAIM**

The ornamental design for a triangular magnetic building tile having a gear shape design, as shown and described.

DESCRIPTION

FIG. 1 is a perspective view of a triangular magnetic building tile having a gear shape design, according to one illustrative embodiment of the design.

FIG. 2 is a side elevation view of the triangular magnetic building tile having a gear shape design as illustrated in FIG. 1, according to one illustrative embodiment of the design, the other side view being a mirror image thereof.

FIG. 3 is a front elevation view of the triangular magnetic building tile having a gear shape design as illustrated in FIG. 1, according to one illustrative embodiment of the design.

FIG. 4 is a top plan view of the triangular magnetic building tile having a gear shape design as illustrated in FIG. 1, according to one illustrative embodiment of the design, the bottom view being a mirror image thereof.

FIG. 5 is a rear elevation view of the triangular magnetic building tile having a gear shape design as illustrated in FIG. 1, according to one illustrative embodiment of the design; and,

FIG. 6 is a top plan view of a tile component of a triangular magnetic building tile having a gear shape design, according to another illustrative embodiment of the design.

In the FIGURES, any broken line in the drawing is not part of the design sought to be patented.
